L. W. BUNDE & W. H. UPMEYER.

BADGE.

No. 15,293.

Patented Aug. 19, 1884.

UNITED STATES PATENT OFFICE.

LOUIS W. BUNDE AND WILLIAM H. UPMAYER, OF MILWAUKEE, WISCONSIN.

DESIGN FOR A BADGE.

SPECIFICATION forming part of Design No. 15,293, dated August 19, 1884.

Application filed June 6, 1884. Term of patent 7 years.

To all whom it may concern:

Be it known that we, LOUIS W. BUNDE and WILLIAM H. UPMAYER, of Milwaukee, in the county of Milwaukee and State of Wisconsin, 5 have originated and invented a new and original Design for Society Badges or Jewels; and we do hereby declare that the following is a full, clear, and exact description thereof, reference being had to the accompanying engraving, forming a part of this specification.

Our design is intended to cover the external configuration of and the ornamentation upon a two-faced badge or jewel; and it consists, primarily, of a peculiarly-shaped shield having the general conventionalized heart shape, but modified in its outlines, as follows: The top 15 of the shield is made with two concave lines set horizontally end to end, and each side edge of the shield consists of a convex line, a little longer than the two concaves of the top line. On the obverse of the shield is the representation of two swords crossed, with their 20 tips projecting above the top line, and the hilts and handles projecting beyond the side lines, so that the said tips, hilts, and handles will show from the reverse side of the shield. On top of the shield are three links, and the tips of the swords project one through each of the outer links, while the center link has 25 an upward ring or loop integral therewith. Across the center of the obverse is a crown above the swords—that is, with the center of the said crown concealing the point of contact of the crossed swords. In the upper part of 30 this side of the shield is an eye surrounded by rays, and these rays are represented as being under the swords when the said parts are in

contact. Beneath the crown, on the obverse side, is shown an open book. On the reverse side of the shield is shown a tent open, and below this three pillars. To the right of the tent are shown two shepherd's crooks, crossed, and to the left of the tent an open right hand, in the palm of which is shown a heart.

Having thus described our design, what we 45 claim as new and original, and desire to secure by Letters Patent, is—

In a design for society badges or jewels, the shield with two concave lines at top, and side edges of convex lines, three links above the 50 shield and two crossed swords on the obverse side of the shield, with the tips projecting above and through two of the links, and with the hilts and handles projecting beyond the side edges, and with a crown on the obverse above the point of juncture of the crossed swords, above this an eye surrounded by rays which extend under the swords, and an open book below the crown, and on the reverse of the shield an open tent under which are three 55 pillars, and with two crossed shepherd's crooks to the right of the tent, and an open hand with a heart on the palm to the left of the tent, substantially as shown.

In testimony that we claim the foregoing we 60 have hereunto set our hands, at Milwaukee, in the county of Milwaukee and State of Wisconsin, in the presence of two witnesses.

LOUIS W. BUNDE.
WILLIAM H. UPMAYER.
